KEY OR SIMILAR ARTICLE

Abraham D. Bobrow, Queens, N. Y.

Application August 11, 1954, Serial No. 31,812

Term of patent 3½ years

(Cl. D50—4)

Fig. 1

Fig. 2

The characteristic features of the design reside in the full line portion as shown.

I claim:

The ornamental design for a key or similar article, as shown and described.
